UNITED STATES PATENT OFFICE.

THOMAS W. MORGAN, OF WATERLOO, IOWA, ASSIGNOR TO WILBUR W. MARSH, OF WATERLOO, IOWA.

DRIVING MECHANISM FOR CENTRIFUGAL LIQUID-SEPARATORS.

No. 822,974.

Specification of Letters Patent.

Patented June 12, 1906.

Application filed May 31, 1905. Serial No. 263,024.

To all whom it may concern:

Be it known that I, THOMAS W. MORGAN, a citizen of the United States of America, and a resident of Waterloo, Blackhawk county, Iowa, have invented certain new and useful Improvements in Driving Mechanism for Centrifugal Liquid-Separators, of which the following is a specification.

My invention relates to driving mechanism for centrifugal liquid-separators; and the object of my invention is to provide a combination of spiral gear-wheels and spiral pinions which will cause a great multiplication of revolutions, which will be most effective and steady in use with a minimum of wear and liability to breakage, and whose elements will so interact as to reduce the pressure within the step-bearings, thus lessening the friction therein. This object I have attained by the mechanism which is hereinafter shown and described, being illustrated by the accompanying drawing, which represents a vertical section of a casing containing my improved form of compound gearing for actuating a centrifugal liquid-separator.

The casing *r* is mounted on a base *x* and is supplied with an elastic collar-bearings *s* for the reception of the spindle *t* of a centrifugal liquid-separator bowl. A sideless boxing *q* is contained within said casing-frame *r* *x* and has perforations in its upper plate for the reception of bearings *o* and in its lower plate for the reception of the step-bearings *n*. Adjusting-nuts *p*, fitted with sleeve-nuts *z*, are placed in the lower ends of the step-bearings *n*. The upper ends of these adjusting-nuts *p* are furnished with hemispherical bosses, on which rest similar hemispherical bosses on the lower ends of the shafts *a*, *d*, and *h*. The upper ends of the shafts *a* and *d* rotate within the bearings *o*, while the shaft *h* passes through an opening in the upper plate of the boxing *q*, and its upper end rotates in a bearing *w*, fitted in a bracket of the casing *r*. The bearing *w* has the adjusting-nut *v* fitted therein, having on its lower end a hemispherical boss which contacts with a similar hemispherical boss on the upper end of the shaft *h*. A two-part horizontal shaft *l* *u* is rotatable in bearings in the upper part of the casing *r* and is fitted with an exterior crank *m*. A large bevel-gear *k* is mounted on the shaft *l*, and its teeth intermesh with the teeth of a small

bevel-gear *i*, mounted on the upper end of the shaft *h*. A spiral gear-wheel *f* is mounted on the lower end of the shaft *h*, and its teeth intermesh with those of the spiral pinion *e*, mounted on the shaft *d*. A spiral gear-wheel *c* is mounted on the shaft *d*, and its teeth engage those of a spiral pinion *b* on the shaft *a*. The upper end of the shaft *a* is constructed of a suitable shape to enter an opening in the lower end of the spindle *t*, while the stud *y* engages the sides of a slot in said spindle. When the gear-wheel *k* is rotated by means of the crank *m*, it imparts rotation to the gear *i*, shaft *h*, and spiral gear *f*, the latter multiplying the revolutions of the spiral pinion *e* and spiral gear-wheel *c* on the shaft *d* and the spiral gear-wheel *c* again multiplying the revolutions of the spiral pinion *b* and shaft *a* with the engaged spindle *t* of the centrifugal liquid-separator bowl.

It will be observed that the directions of rotation of the spiral gear-wheels *f* and *c* are reversed in relation to each other. The result of this reversal in the engagement of said spiral gear-wheels with the spiral pinions *c* and *b*, respectively, is when they are in rapid rotation to exercise a lifting stress upon the shaft *a* and its attached superincumbent spindle *t* of the separator-bowl, which greatly relieves the pressure upon and friction between the surfaces of the opposing bosses in the step-bearing. The added result is obtained of greater ease of operation and a steadier motion of revolution. The use of spiral gear also creates greater wearing-surfaces along the contact edges of the teeth of each, thus preventing rapid wear and making the gearing longer lived.

Having described my invention, what I claim as new, and desire to secure by Letters Patent, is—

1. A driving mechanism for centrifugal liquid-separators, comprising a removable boxing, bearings in said boxing, a rotatable shaft, a spiral gear-wheel mounted thereon, a rotatable shaft, a spiral pinion thereon intermeshing with said spiral gear-wheel, a spiral gear-wheel on said spiral-pinion shaft, a rotatable shaft, a spiral pinion thereon intermeshing with the last-mentioned spiral gear-wheel, and a driven spindle actuated by said last-mentioned shaft.

2. A driving mechanism for centrifugal liq-

2
uid-separators, comprising an external cas-
ing, a removable hollow boxing therein, anti-
friction-bearings in said boxing, shafts
mounted in said bearings, a crank, inter-
meshing spiral gearing on said shafts ar-
ranged to drive a spindle, and a driven spin-
dle.

3. A driving mechanism for centrifugal liq-
uid-separators, comprising a rotatable shaft,
10 a bevel-gear mounted thereon, a boxing in
said casing provided with bearings, a rotatable
shaft in said boxing having a bevel gear
wheel intermeshing with said first-mentioned
bevel gear-wheel, a spiral gear-wheel mounted
15 on said bevel-gear shaft, a rotatable shaft, a
spiral pinion thereon intermeshing with said
spiral gear-wheel, a spiral gear-wheel on said
spiral-pinion shaft, a rotatable shaft, a spiral
pinion thereon intermeshing with the last-
20 mentioned spiral gear-wheel, and a driven

spindle actuated by said last-mentioned
shaft.

4. A driving mechanism for centrifugal liq-
uid-separators, comprising a suitable boxing,
a driven spindle, rotatable shafts in said box-
ing, intermeshing spiral gear-wheels and spi-
ral pinions on said shafts so arranged that the
directions of revolution of both the gear-
wheels and the pinions are respectively re-
versed in relation to each other producing a 30
lifting stress by reason of their coöperation
upon the driven spindle, substantially as de-
scribed.

Signed at Waterloo, Iowa, this 20th day of
March, 1905.

THOMAS W. MORGAN.
